UNITED STATES PATENT OFFICE.

BYRON E. BOWLES, OF COUNCIL BLUFFS, IOWA.

WINDOW-SASH FASTENER.

Application filed November 10, 1924. Serial No. 748,913.

To all whom it may concern:

Be it known that BYRON E. BOWLES, a citizen of the United States, residing at Council Bluffs, in the county of Pottawattamie and State of Iowa, has invented certain new and useful Improvements in Window-Sash Fasteners, of which the following is a specification, reference being had therein to the accompanying drawings.

- 10 The invention relates to window sash fasteners and has for its object to provide a device of this character comprising acutely angled lever pivotally mounted in a casing mortised in the side of the sash, and having one of its arms provided with a member extending through an aperture in the sash and cooperating with an apertured plate carried by the window frame for holding the window sash in various positions, for ventilating purposes and preventing the window sash from being raised or lowered.

A further object is to provide leaf spring within the casing and cooperating with one of the arms of the lever for normally moving the lever to locked position, and a rotatable key operated cam cooperating with the spring engaged arm of the lever for moving the lever to inoperative position and holding the same in inoperative position.

25 With the above and other objects in view the invention resides in the combination and arrangement of parts as hereinafter set forth, shown in the drawing, described and claimed, it being understood that changes 30 in the precise embodiment may be made within the scope of what is claimed without departing from the spirit of the invention.

In the drawing:

Figure 1 is a front elevation of a portion of a sash and a portion of a window frame showing the locking device applied thereto.

Figure 2 is a perspective view of the locking device showing a portion of its casing broken away, and the parts in unlocked position.

Figure 3 is an enlarged view in elevation of one of the side rails of the sash showing the locking device.

Figure 4 is a vertical longitudinal sectional view through the locking device.

Figure 5 is a perspective view of the rotatable cam.

Figure 6 is a view in elevation of the key.

Figure 7 is a view in elevation of the inner side of the key hole guard plate.

Figure 8 is a horizontal sectional view through a portion of the sash and window frame and the locking device taken on line 8-8 of Figure 1.

Referring to the drawing, the numeral 1 designates the window sash which may be the upper or lower sash, and 2 a portion of the window frame. Mortised into the rail 3 of the sash as at 4 is the casing 5 of the locking device. Pivotally mounted at 6 within the casing 5 adjacent its upper inner end is an acutely angled shaped lever 7. The arm 8 of the lever 7 is substantially vertically disposed adjacent the inner wall 9 of the casing and with which arm the leaf spring 10 carried by the wall 9 of the casing operates for normally forcing the free end of the arm 8 in the direction of the arrow *a*, for forcing the downwardly and outwardly inclined arm 11 of the lever 7 in the direction of the arrow *b*, and its angularly shaped extension 12 outwardly through the opening 13 in the outer wall of the casing 9 where it will engage the window frame 2 between the stops 14 and be received in apertures 15 carried by the frame for holding the window sash 1 in various adjusted positions in a manner whereby the sash can not be raised or lowered, consequently the window sash may be locked and held in various open positions sufficient for ventilating purposes, but at the same time, not open to the extent an unauthorized person may enter above or below the sash. Although the device has been described and shown in connection with one side of a sash, it is to be understood that as many of the devices as desired may be applied to the sash, whether upper or lower sash.

Rotatably mounted within the casing 5 is a cam 16 which cam is provided with pintles 17 which are rotatably mounted in opposite walls of the casing 5, however one of said pintles 17 is provided with a slot 18 in registration with an opening 19 in one side of the sash rail 3, and through which opening the key 20 is adapted to extend so its flat end 21 may be received in the slot 18 for rotating the cam 16. When the cam 16 is in the position shown in Figure 2, the lever 7 is moved to unlocked position, however when the cam 16 is in the position shown in Figure 4, the locking lever 7 is in locked position and held in locked position by the leaf spring 10, therefore it will be seen that a positive locking device is provided. The key receiv-

- ing aperture 19 may be provided with a key hole guard 22 for preventing marring of the sash frame when placing the key 20 therein.
- 5 From the above it will be seen that a locking device is provided for window sash, which is positive in its operation, and one which will positively hold the window sash and will practically be entirely concealed 10 from view thereby not detracting from the appearance of the window sash, is key operated, and one which may be easily and quickly applied to a window sash without varying the construction thereof.
- 15 The invention having been set forth what is claimed as new and useful is:—
The combination with a window sash, said sash being slidably mounted in a window frame, of a locking device for said sash, said 20 device comprising a casing mortised in the side of the sash and having its outer side open, an inverted V-shaped lever pivotally
- mounted within the casing adjacent its upper inner corner, said lever having a downwardly extending arm adjacent the rear side of the casing, a leaf spring disposed within the casing and normally forcing said arm outwardly at its free end, a downwardly and outwardly extending arm carried by the V-shaped lever, said last named arm terminating in an angularly shaped member co-operating with the window frame, a cam rotatably mounted within the casing between the arms and cooperating with the first mentioned arm for forcing the same inwardly 35 against the action of the leaf spring, said cam having its opposite sides provided with bosses rotatably mounted in opposite walls of the casing, one of said bosses registering with an aperture in the sash and provided 40 with key receiving means.

In testimony whereof I hereunto affix my signature.

BYRON E. BOWLES.
